MOBILE LAWN SPRINKLER

John D. Beinert, Babylon, N.Y., assignor to International
Patent Research Corp., New York, N.Y., a corporation
of New York

Filed Oct. 6, 1961, Ser. No. 66,990

Term of patent 7 years

(Cl. D91—1)

FIG. 1

FIG. 2

FIG. 3

FIG. 4

FIG. 1 is a side elevational view of a mobile lawn sprinkler showing my new design;

FIG. 2 is a top plan view thereof;

FIG. 3 is a side elevational view thereof, taken from the left hand side of FIG. 1; and

FIG. 4 is a side elevational view thereof, taken from the right hand side of FIG. 1.

I claim:

The ornamental design for a mobile lawn sprinkler, as shown.
